UNITED STATES PATENT OFFICE

ARCHIBALD ALLAN, OF TYNEMOUTH, ENGLAND, ASSIGNOR TO A. REYROLLE & COMPANY LIMITED, OF HEBBURN-ON-TYNE, ENGLAND, A REGISTERED COMPANY OF GREAT BRITAIN

ELECTRIC COUPLING

Application filed January 10, 1930, Serial No. 419,985, and in Great Britain February 19, 1929.

This invention relates to electric couplings of the kind often used in switch gear wherein a conductor terminating say in a plug or socket and surrounded by a hollow porcelain or like insulator itself surrounded by a metal casing, operates in conjunction with another conductor usually mounted in an insulating bushing and terminating in a socket or plug.

10 In such couplings various arrangements have been suggested to prevent excessive electrostatic stress in the solid or other insulating materials or media or to equalize or distribute such stresses evenly with a view to 15 preventing breakdown or corona discharge at high voltages. In one such arrangement a recessed portion or neck of the insulator surrounding one conductor has been surrounded by a metal band or sheath in electrical contact with the conductor.

The present invention has for its object the construction of a coupling of the general kind above referred to wherein the prevention of the excessive electrostatic stress is 25 very effectually provided for.

In an electric coupling according to this invention the hollow or orifice insulator is surrounded by oil or insulating compound in a metal casing, and surrounding the insulator and in close proximity to the main body of it is a metal shield connected to the conductor on which the insulator is carried, such metal shield extending sufficiently far over the hollow part or orifice of the insulator as to shield the other cooperating conductor and its bushing and confine the electrostatic stress to the oil or compound between the shield and the casing.

Two constructions of coupling according 40 to the invention will now be described by way of example with reference to the accompanying drawings, in which

Figure 1 shows an elevation of the coupling with the hollow or orifice insulator in 45 section,

Figure 2 is an elevation on a reduced scale of a modified form of coupling, the hollow or orifice insulator being shown partly in section.

50 In the arrangement shown in Figure 1 the

hollow or orifice insulator A is bell-shaped and is clamped to a conductor B, which terminates inside the inner end of the insulator in a contact block B¹, by means of a nut B². The contact block B¹ cooperates with 55 finger or spring contacts C carried by a metal cap C¹ mounted on the end of an insulating bushing D through which the conductor to the contacts C passes.

Surrounding the insulator A and clamped 60 to the conductor B by means of the ring B³ is a metal shield E which is also bell-shaped. The shield E extends in close proximity to the main body of the insulator to a position, as indicated by the broken line E¹, somewhat 65 below the metal cap on the bushing D and terminates in an internally rounded or beaded edge E². The whole arrangement is surrounded by a metal casing F, the space between this casing and the shield being filled 70 with oil or insulating compound.

The arrangement shown in Figure 2 is similar to that of Figure 1 with the exception that the bell-shaped metal shield E is replaced by metallic shield E⁴ formed on the 75 outer surface of the orifice insulator and connected to the insulator clamping nut B². This metallic shield may be formed by any suitable metallizing process, by painting with a metallic paint or by thin metal foil or wire 80 wound on or otherwise fixed to the surface of the insulator.

In either of the above constructions the electrostatic stress is practically confined to the oil or compound between the shield and 85 the casing and danger from breakdown through undue stress in the air gap within the orifice insulator eliminated.

It will be appreciated that the above description is by way of example only and that modifications may be made in the detailed construction of the arrangement within the scope of the invention. Although the coupling is shown in the drawing in a vertical 90 position it is to be understood that the invention is equally applicable to couplings of either the horizontal or the vertical draw-out or plug-and-socket type or to couplings 95 inclined at any angle.

What I claim as my invention and desire to secure by Letters Patent is:—

1. In an electric coupling the combination of a conductor, a hollow insulator carried by and surrounding said conductor, a second conductor cooperating with the first conductor to make and break electrical contact therewith, an insulating support or bushing for said second conductor, a metal shield connected to the first conductor and closely surrounding said hollow insulator and extending sufficiently far over its surface to shield said second conductor and part of its bushing, and an outer metal casing surrounding the whole coupling and separated therefrom by insulating medium.

2. An electric coupling comprising the combination of a first contact member, a hollow insulator surrounding the said member and carried thereby, a second contact member for cooperating with the first member, an insulating bushing carrying the second member and arranged to be inserted within the hollow insulator to effect the engagement of the members, a metal casing surrounding the hollow insulator, insulating medium between the insulator and the casing, and a metallic shield surrounding and in close proximity to the insulator, said shield being connected to the first contact member and extending over the hollow insulator so as to surround the second member and part of its bushing and to confine the electrostatic stress to the insulating medium between the shield and the casing.

3. An electric coupling including in combination a conductor, an orifice insulator carried thereby, a first contact within the insulator and connected to the conductor, a second cooperating contact, an insulating bushing carrying said second contact and adapted to be inserted within the insulator to effect the engagement of the contacts, an outer metal casing surrounding the insulator, insulating oil between the casing and the insulator, and a metal shield carried by and closely surrounding the insulator, said shield extending sufficiently far over the orifice part of the insulator to shield the contacts and part of the bushing and to confine the electrostatic stress to the oil between the shield and the outer metal casing.

In testimony whereof I have signed my name to this specification.
